UNITED STATES PATENT OFFICE.

HANS SCHWEITER, OF HOREN, SWITZERLAND.

APPARATUS FOR COATING TEXTILE THREADS WITH A SOLID SUBSTANCE.

Application filed January 13, 1923, Serial No. 612,539.

To all whom it may concern:

Be it known that I, HANS SCHWEITER, a Swiss citizen, residing at Horgen, in the Canton of Zurich, Switzerland, have invented a new and useful Improvement in Apparatus for Coating Textile Threads with a Solid Substance, of which the following is a specification.

This invention relates to apparatus for 10 coating textile threads with a solid substance, chiefly paraffine, in which the thread is drawn between the two substance blocks which are pressed together by springs and are rotated by the pull on the thread by 15 means of a toothed wheel drive.

According to my invention the carriers of 20 the substance blocks together with the toothed wheel belonging thereto is arranged oscillatable in a forward direction on the bracket of the apparatus for the purpose of 25 enabling replacement of the substance blocks from the front of the apparatus without requiring additional room.

The previously known method of changing 30 the substance blocks from the side of the apparatus was inconvenient and required much room.

I attain the objects aimed at by the mechanism illustrated in the accompanying drawings, in which—

Figure 1 is a front elevation and

Figure 2 a left-hand side elevation of one 35 constructional example, showing the substance blocks in operative position.

Figure 3 is a similar elevation to Figure 1 and Figure 4 a similar elevation to Figure 2, but partly in vertical section and showing the substance blocks swung 90 degrees forwards.

40 Figures 5 and 6 are horizontal sections on line 5—5 of Figure 1, the substance blocks and their carrier sleeve being removed in Figure 6.

Figure 7 is a detached front elevation,

45 Figure 8 is a detached side elevation, and

Figure 9 is a plan view illustrating another construction.

Referring to Figures 1 to 6, an angular 50 apparatus bracket 2 is adjustably fixed by a set screw to the horizontal supporting rod 1. The horizontal part of the bracket 2 carries the thread guide 4 and the thread guiding roller 5, whilst the vertical part of the bracket 2 carries an axle pin 6 on which a 55 boss 7 is mounted, the boss 7 being provided

with a pinion 8 and a guiding and driving pulley 9.

A semi-circular disc 12 provided with apertures 10 and a rim flange 13, and serving to carry the substance blocks, for example 60 paraffine blocks 11, has two diametrically opposite lugs 14 having bearing cavities 15 for two pivot screws 17 screwed into lugs 16 formed on the vertical part of the bracket 2. At the axis of the disc 12 there is fixed an 65 axle pin 18 onto which a sleeve 19 is pushed. There is fixed to the sleeve 19 one end of a tube 20, Figure 6, which is swelled out between its ends and divided into resilient laminae by longitudinal slits. The boss 21 70 of the wheel 22 which meshes with the pinion 8 is fixed on the sleeve 20.

Onto the spring tube 20 is pushed the carrier sleeve 24, and the resilient laminae of the tube 20 produces a rigid connection between the tube 20 and the sleeve 24. The sleeve 24 has a cylindrical bore, is externally of square cross-section and is of resistant material, for example, porcelain. The substance blocks 11 are axially broken through 80 to correspond with the external cross-section of the sleeve 24 and are pressed against each other by springs 7 placed on the sleeve 24 and held in position by spring wire stirrups 26, Figures 3 and 5, pushed into grooves 25 85 in the sleeve 24. The sleeve 24 is also provided with an annular groove 23 which lies in the plane of contact of the blocks 11 and the thread 28 is drawn between the blocks 11 and at the same time engages the groove 90 23 in the sleeve 24.

When the apparatus is in operation, the disc 12 together with the substance blocks 11 are in the positions illustrated in Figures 1 and 2, the disc 12 being fixed in the working 95 position by means of a screw-threaded pin 32 screwed into a lug 29 and engaging an eye lug 30 on the disc 12 and connected by a chain 31. The pull on the thread sets the pulley 9, the toothed gearing 8, 22, the 100 sleeve 19, the tube 20 and therefore the substance blocks 11 in rotation for the purpose of effecting a uniform using up of the blocks 11.

After the blocks 11 have been used up, 105 the pin 32 is withdrawn and the disc 12 is oscillated in a forward and sidewise direction into the position illustrated in Figures 3 and 4. The carrier sleeve 24 is then drawn in a forward direction off the spring tube 110

20 and has new substance blocks 11 placed on it, whereupon it is again pushed on to the spring tube 20. The disc 12 and the new substance blocks 11 are then again oscillated back into their working positions and secured therein. On the forwards and backwards oscillation of the disc 12 the wheel 22 comes out of and into engagement with the pinion 8. It will be appreciated that for 10 renewing substance blocks no additional room is required as is necessary in the case where renewal of the blocks takes place from the side. Thus a larger number of apparatus than hitherto can be mounted on the 15 carrying rod. Furthermore the renewal of the blocks from the front is handier than renewal from the side.

In the construction illustrated in Figures 7 to 9 the parts are the same as described 20 with reference to the first construction with the exception that the thread guiding roller 5 is higher and is arranged above the thread clearer provided on the horizontal part of the bracket 2. The thread clearer has a stirrup 33 secured to the said part and carrying 25 on its arms jaws 34 adapted to be adjusted by means of screws and serving to clear the thread 28 passing between them. The cleared thread then passes to the substance 30 blocks 11.

I claim:

1. An apparatus for coating textile threads with a solid substance, chiefly paraffine, comprising a bracket, a carrier adapted to swing sidewise on the bracket relative to the apparatus when fixed in working position, means rotatable on the carrier to receive blocks of solid coating substance, a toothed wheel rotatably mounted on the carrier and rotatively connected with the said means, and means rotated by the thread and adapted to rotate the said wheel.

2. An apparatus for coating textile threads with a solid substance comprising 45 a stationary bracket, a carrier on the bracket capable of being swung out of its working position sidewise relative to the apparatus

tus fixed in its working position and considered from the front, rotatable means on the carrier for receiving blocks of the coating substance, a toothed wheel on the carrier rotatably connected to the said means and swingable sidewise with the carrier, a rotatable toothed driving wheel on the stationary bracket and meshing with the first 55 named toothed wheel only when the carrier is in its working position, and disengageable locking means on the bracket for retaining the carrier in its working position against sidewise movement on the bracket. 60

3. An apparatus for coating textile threads with a solid substance comprising a support which is oscillatable sidewise relative to the apparatus as considered from the front when in working position, a solid substance holder rotatable on the said support, and a thread clearer provided on the support where the thread can pass through it before the thread comes into contact with the solid substance. 65

4. An apparatus for coating textile threads with solid substance comprising a bracket, two pivots provided in alignment thereon, a disc adapted to be swung on the said pivots in a direction which is sidewise 75 and forwards relative to the apparatus as considered from the front when in its working position, a bearing pin fixed to the disc, at an angle to the aligned pivots, a sleeve rotatably mounted on the pin, a toothed 80 wheel fixed to the said sleeve, a slip-on sleeve placed on the rotatable sleeve and adapted to receive blocks of the coating substance, thread guide means on the bracket, a bearing pin on the said bracket, a rotatable sleeve on the said pin, a thread guide pulley rigidly connected to the said sleeve and a pinion rigidly connected to said sleeve and meshing with the said toothed wheel. 85

Signed at Zurich, in the Canton of Zurich, Switzerland, this 29 day of December 1922.

HANS SCHWEITER.
